UNITED STATES PATENT OFFICE.

CHARLES E. CATHER, OF WORCESTER, MASSACHUSETTS, ASSIGNOR TO UNITED STATES ENVELOPE COMPANY, OF SPRINGFIELD, MASSACHUSETTS, A CORPORATION OF MAINE.

DUPLEX ENVELOPE.

Application filed March 18, 1921. Serial No. 453,362.

The object of my present invention is to provide an envelope having two separate pockets, one of which is capable of being securely sealed and adapted to receive 5 postal matter of the first class, and the second of said pockets is adapted to receive bulky matter, such for instance, as circulars or catalogues mailable at a lesser rate than first class matter. I accomplish this result 10 in the manner hereinafter described and illustrated in the accompanying drawings, in which

Fig. 1 represents a blank, shown in its extended form, from which my improved 15 envelope is folded.

Fig. 2 represents a completed envelope folded from the blank shown in Fig. 1.

Fig. 3 represents a modified form of the blank, and

20 Fig. 4 is a completed envelope as constructed from the blank represented in Fig. 3.

Like reference characters refer to like parts in the different figures.

25 The blank from which my envelope is constructed, as represented in Fig. 1, consists of a body portion 1, having at one end a closing flap 2 and at the opposite end an end flap 3 having a gummed portion 4.

30 On one side of the body portion 1 I provide a side flap 5, substantially the same width as the body portion 1, and on the opposite side of the body portion 1 I provide a side flap 6, provided with a gummed sur-

35 face 7 on its outer longitudinal side, and having near its center a narrow gummed surface 8 extending transversely across the side flap. The side flap 6 is preferably pro-

40 vided with a window opening 9 above the gummed surface 8 and parallel with the edge of the folded envelope. The side flap 5 is provided with a seal flap 10, having on its reverse side a gummed surface 11.

45 In the operation of folding, the side flap 5 is folded on the dash and dot line 12 upon the body portion 1. The side flap 6 is next folded on the dash and dot line 13 upon the side flap 5, to which it adheres by means of the gummed surfaces 7 and 8. The end 50 flap 3 is next folded upon the dash and dot line 14 upon the side flaps 5 and 6, completing the envelope which is represented in

Fig. 2, in which the body portion 1 and side flap 5 form a pocket for second class matter, and the side flap 7 and the side flap 5 form 55 a pocket for first class matter.

The pocket for first class matter is securely sealed by the sealing flap 10, the adhesion of the side flap 7 to the side flap 5, as indicated by the broken lines 15 and 16, forming the bottom of the pocket for first class matter, which is preferably so folded that the address will be disclosed through the window opening 9. The pocket for second class matter is closed by the flap 2, which 60 may be tucked in or otherwise secured in any suitable and well known manner.

65 In Figs. 3 and 4 I have shown a slight modification in the form of the blank, in which 17 denotes the body portion of the 70 envelope, having at one end a closing flap 18, and at the opposite end an end flap 19 provided with a gummed surface 20. Upon one side of the body portion 17 I provide a side flap 21, of substantially the same width as the body portion 17, and upon the opposite side of the body portion 17 I provide a side flap 22 of the same width, having a longitudinal gummed margin 23 and a transverse line of gum 24. The side flap 23 is prefer- 75 ably provided with a window opening 25 parallel with the gummed surface 24.

80 The blank, as shown in Fig. 3, is folded upon the dash and dot line 26 to bring the side flap 21 over the body portion 17. The 85 side flap 22 is next folded on the dash and dot line 27 over the side flap 21, to which it adheres by means of the gummed surfaces 23 and 24. The end flap 19 is next folded upon the side flap 22, to which it adheres 90 by means of the gummed surface 20. The side flap 21 is provided with a sealing flap 28, having upon its reverse side a gummed surface 29. When the blank has been folded, it will assume the form shown in Figure 4, in 95 which a pocket for first class matter will be formed between the two side flaps, with the bottom of the pocket indicated by the broken lines 30 and 31. This pocket may be securely sealed by the gummed sealing flap 28, and with the address upon the inclosure disclosed through the window opening 25.

100 The pocket for second class matter will be formed between the body portion 17 and the side flap

21, and may be closed by the flap 18, which may be tucked in or secured in any other suitable manner. The bottom of the pocket for second class matter will be closed by the 5 gummed flap 19, when the blank shown in Fig. 3 is used. When the blank shown in Fig. 1 is used, the pocket for second class matter will be closed by the end flap 3.

I am aware that duplex envelopes have 10 been heretofore used and I do not claim such broadly, but what I do claim and desire to secure by Letters Patent is:—

1. A double compartment envelope comprising a blank having a body portion, a relatively large side flap extending from one edge of said body portion and folded over said body portion to provide a relatively large compartment between said large flap and body portion, said large flap being 15 approximately equal in length and width to said body portion, a relatively small side flap extending from said body portion at the edge opposite to the first mentioned edge, said small side flap being folded over said 20 large side flap to provide a second compartment directly between said side flaps, the two compartments having one common boundary line, said small side flap having a gummed margin sealed to the outer face of 25 said large side flap in a line between and parallel with said edges, an end flap extending from the lower edge of said body portion and sealed to the outer faces of both of said side flaps, a gummed sealing flap extending from the upper edge of said large side 30 flap and foldable over said small side flap, the length of said gummed sealing flap being approximately equal to the width of said small side flap so as to form a closure for 35 said second compartment, and a non- 40 sealing closure flap extending from the upper edge of said body portion to form a closure for said relatively large compartment.

sealing closure flap extending from the upper edge of said body portion to form a closure for said relatively large compartment.

2. A double compartment envelope comprising a blank having a body portion, a 45 relatively large side flap extending from one edge of said body portion and folded over said body portion to provide a relatively large compartment between said large flap and body portion, said large flap being 50 approximately equal in length and width to said body portion, a relatively small side flap extending from said body portion at the edge opposite to the first mentioned edge, said small side flap being folded over said 55 large side flap to provide a second compartment directly between said side flaps, the two compartments having one common boundary line, said small side flap having a gummed margin sealed to the outer face of said large 60 side flap in a line between and parallel to said edges, said small flap being provided with an aperture forming a window through which an address may be exposed in said second compartment, an end flap extending from the lower edge of said body portion and sealed to the outer faces of both of said side flaps, a gummed sealing flap extending from the upper edge of said large side 65 flap and foldable over said small side flap, the length of said gummed sealing flap being approximately equal to the width of said small side flap so as to form a closure for 70 said second compartment, and a non-sealing closure flap extending from the upper edge 75 of said body portion to form a closure for said relatively large compartment.

Dated this tenth day of March, 1921.

CHARLES E. CATHER.
